ASH TRAY

Fridl Kohn, née Meier, New York, N. Y.

Application October 8, 1938, Serial No. 233,920

4 Claims. (Cl. 131—237)

My invention relates to improvements in ash trays for the residue of cigarettes, cigars and tobacco.

It is well-known that if a burning butt of a cigarette or cigar or burning tobacco is placed in an ash tray, a disagreeable and disturbing odor is created by the smoke ensuing from the burning butt. An attempt to extinguish a cigarette or cigar by pressing it by hand against the bottom of the ash tray is often not successful as daily experience teaches, and, more or less, slight burns are often the consequence of such attempts. It also often happens that a careless person places a burning butt in an ash tray without troubling to snuff it, another party may have the unpleasant and unhygienic task of attempting to complete the job.

One object of my invention is a combination of a snuffer and of an ash tray which makes it possible to snuff any burning butt placed in the ash tray in a safe and sanitary manner, and which secures that it is always in a position ready for use.

Another object of my invention is to arrange the snuffer in such a manner that it is normally held in a position in which it does not interfere with the use of the ash tray, and that it can be gripped and pressed against any butt lying in the ash tray. The snuffer is further arranged in such a manner that it is automatically returned to its original position if released.

Other and further objects and advantages of my invention will be hereinafter set forth and the novel features thereof defined by the appended claims.

In the accompanying drawing several embodiments of my invention are shown.

Figure 1 is a plan view of an ash tray according to my invention.

Figure 2 shows a side view of the ash tray according to Fig. 1 the parts being partly broken away.

Figure 3 is a longitudinal section of the snuffer shown in Fig. 1.

Figure 4 is a longitudinal section of a second embodiment of a snuffer according to my invention and

Figure 5 is a longitudinal section of a third embodiment of a snuffer according to my invention.

An ash tray according to my invention comprises a bowl 1 which can have any shape. It can consist of metal or any suitable synthetic material for example, of such material as known under the trade name "bakelite." Of course, it

is also possible to compose the bowl of several materials as for instance, wood or metal. It is often convenient to attach to the bowl 1 a receptacle 2 for matches and one or more holders 3 for cigarettes or cigars.

According to my invention a support 4 is provided which can be connected with the bowl 1 by any suitable means. In the embodiment shown in Figures 1 and 2 two arms 5 and 6 are provided having ear holes through which the lower section of support 4 projects, which ends in a threaded bolt 7. On this bolt a nut 8 is screwed which fixes support 4 in its position. However it is also possible that the support is integral with bowl 1 itself. The support 4 has an arm 9 which ends in an element 10 for example a ball provided with an ear 11. From this ear a snuffer 12 is suspended.

Figures 3, 4 and 5 show several embodiments of snuffers 12.

In Figure 3 the snuffer consists of a hollow cone 13 of any suitable material, the bottom of which is adapted to be pressed against any burning residue of cigars, cigarettes or tobacco placed in the bowl 1 for instance, against a cigarette butt in order to snuff it. The suspension of the snuffer is accomplished by a rod 15, the upper end of which is by means of an ear 16 pivotally connected with ear 11. The lower end of the rod ends in a little disc 16. Rod 15 is surrounded by a coil spring 17, which abuts with one end against the upper wall of the cone 13 and with the other end against the disc 16.

Normally the snuffer is in the position which is shown in Figure 2 in unbroken lines. If any burning residue for instance, a cigarette butt 18 which is to be snuffed out is placed in the bowl snuffer 12 is gripped and pushed downward as shown in broken lines so that the butt is pressed between bottom 14 and the bowl 1. Thereby it is snuffed in a clean and safe manner and without any necessity for touching the butt itself. By pulling down the snuffer coil 17 is compressed between disc 16 and the upper wall of the cone 13. Consequently the snuffer is snapped into its upper position as soon as it is released.

Hereby I secure that the snuffer never interferes with the use of the bowl, it is always at hand and will not get lost.

In Figure 4 a rod 19 is provided which is pivotally connected with ear 11 in the same manner as rod 15 but which ends in a hook 20. Between this hook and a second hook 21 screwed into bottom 14 of the snuffer a coil spring 22 is provided. This spring has always the tendency to hold the

snuffer in its upper position shown in Fig. 2 as can be easily understood. As soon as the snuffer is pulled downward to snuff a cigarette butt spring 22 is stretched. Consequently it pulls the snuffer back into its upper position after the snuffer is released.

In Figure 5 the suspension of the snuffer is also effected by means of rod 19, hook 20, hook 21 and coil spring 22. The snuffer itself consists of several telescoped sections 23, 24, and 25. As can be easily understood spring 22 tends to hold the snuffer in an upper position equivalent to the position of the snuffer shown in Fig. 2 and has at the same time the tendency to pull telescopic sections 23, 24, and 25 as close together as possible. When the snuffer is pulled downward spring 22 is stretched and the telescopic sections are extended so that the bottom of the bowl can easily be reached. As soon as the snuffer is released it returns to its original position by the pull of the stretched spring 22.

Form and shape of the snuffer can be changed in various ways. Especially, it is possible to give the snuffer the form of any animal or any other figure which is deemed to be suitable or attractive. It is essential only that there is an elastic connection between the snuffer and its support by means of which the snuffer can be brought into contact with any residue placed in the bowl and is returned automatically to its original position if released.

While the specific details of construction have been herein shown and described my invention is not confined thereto as changes and alterations may be made without departing from the spirit of the invention as defined by the appended claims.

Having thus described my invention what I claim as new and desire to secure by Letters Patent is:

1. In an ash tray in combination, a bowl for the residue of cigars, cigarettes and tobacco, a hollow snuffer adapted to be pressed against burning residue of cigars, cigarettes or tobacco placed in the bowl in order to snuff the residue, a gallows-shaped support attached to said bowl, said support including an arm extending above the bowl, a rod pivoted with one end to said

arm and injected with its other end in said hollow snuffer and a coil spring arranged within said hollow snuffer, one end of said coil spring connected to a wall of said snuffer and the other end connected to said rod.

2. In an ash tray in combination, a bowl for the residue of cigars, cigarettes and tobacco, a hollow snuffer adapted to be pressed against burning residue of cigars, cigarettes or tobacco placed in the bowl in order to snuff the residue, a gallows-shaped support attached to said bowl, said support including an arm extending above the bowl, a rod pivoted with one end to said arm and injected with its other end in said hollow snuffer and a coil spring arranged within said hollow snuffer and surrounding said rod, one end of said coil spring abutting against a wall of said snuffer and the other end attached to said rod.

3. In an ash tray in combination, a bowl for the residue of cigars, cigarettes and tobacco, a snuffer shaped as a hollow cone, the base of which is adapted to be pressed against burning residue of cigars, cigarettes or tobacco placed in the bowl, in order to snuff the residue, a gallows-shaped support attached to said bowl, said support including an arm extending above said bowl, a rod pivoted with one end to said arm and injected with its other end into the vertex of said cone and a coil spring arranged within said hollow cone, one end of said coil spring connected to a wall of said cone and the other end connected to said rod.

4. In an ash tray in combination, a bowl for the residue of cigars, cigarettes and tobacco, a gallows-shaped support attached to said bowl, said support including an arm extending above said bowl, a hollow snuffer adapted to be pressed against the burning residue of cigars, cigarettes and tobacco placed in the bowl to snuff said residue, a rod pivotally connected with said arm and projecting into said hollow snuffer, said rod permitting said snuffer to assume either an upper position above and separated from said bowl or a lower position in which said snuffer may be pressed against residue in said bowl and a spring provided within said snuffer tending to hold said snuffer in its upper position.
